RAIL FLAW INSPECTION MECHANISM

George Lester Jones, Garden City, N. Y., assignor
to Sperry Products, Inc., Brooklyn, N. Y., a
corporation of New York

Application August 4, 1936, Serial No. 94,177

3 Claims. (Cl. 175—183)

This invention relates to rail flaw detector mechanisms of the type employed upon the Sperry rail flaw detector cars. The principle upon which these cars operate is now well known and consists in passing current between spaced points on the rail to establish an electromagnetic field surrounding the same. Said field will be uniform except in the region of a flaw where it will be distorted, and such distortion is detected by means such as one or more pairs of induction coils to generate an E. M. F. which may be caused to operate suitable indicating mechanism. Such mechanism may take the form of a recorder or other suitable indicator within the car and a rail marking mechanism such as a paint gun adapted to squirt paint upon the rail in the region of flaw. It will be understood that such distortion of the electromagnetic field will be caused not only by fissures within the rail but also by such conditions as surface burns, corrugated formations of the rail surface, and so forth, which serve to distort the field and operate the paint mechanism in a manner similar to internal defects. It is, therefore, necessary to investigate these paint marks on the rail by hand testing to determine which of them is caused by real internal defects which it is the object of the detector mechanism to detect, and which of them is caused by surface defects which are not harmful and which do not affect the utility of the rail.

It is the principal object of this invention to provide means which facilitate the investigation of said paint marks by hand testing. In an average test day there may be as many as 200 such paint marks, so that the necessity for rapid investigation of these marks will become apparent.

Further objects and advantages of this invention will become apparent in the following detailed description thereof.

In the accompanying drawing,

Fig. 1 is a side view of a portion of a car having my hand test equipment applied thereto.

Fig. 2 is a plan view of the Figure 1 mechanism, the car roof having been removed.

Referring to the drawing, I have disclosed a car 10, only a portion of which is shown, said car riding upon rails R. This car may be the standard Sperry rail fissure detector car which locates points of electromagnetic distortion in the rail and marks the same, or it may be a Sperry inspection car which is adapted to follow the standard Sperry detector car for the sole purpose of investigating the marks left upon the rail by the detector car. My hand testing mechanism is the same in either case and is similarly mounted upon the respective car. In either case I mount upon one end of the car 10 an open supporting frame-work which may comprise side

truss members 11, 11', cross member 12 joining said truss members at the outer ends, and cross member 12' joining said truss members adjacent their inner ends, said truss members being fixed to the frame 14 of the car body at their inner ends. The side members 11, 11' extend upwardly from the frame 14 to permit mounting the various mechanisms thereon. Fixed to each truss member 11, 11' at spaced points are two fluid pressure cylinders 15, 16 and 15', 16', the cylinders 15, 15' being preferably adjacent the car 10 while the cylinders 16, 16' are positioned outwardly of the car at a predetermined distance of several feet. Fluid pressure to each pair of fluid pressure cylinders 15, 16 and 15', 16' may be separately controlled by means of valves 17, 17' within the car body 10. Each valve controls the supply of fluid pressure to both cylinders of the respective pair, the said cylinders having a common fluid pressure supply pipe 20, 20'. When the operator within the car discovers a paint mark on the rail which should be investigated for possible internal defect, he positions car 10 so that the paint mark appears within the open frame-work 11, 11', 12, 12' between cylinders 15, 16 or 15', 16'. The open frame-work enables the operator to locate the hand test mechanism carried thereby in proper position with respect to the paint mark on the rail. The operator then opens valve 17 or 17' to permit fluid pressure, such as compressed air, from a source, such as tank 25 within the car, to be delivered to the respective pair of cylinders 15, 16 or 15', 16'. This causes piston-rods such as 26 and 27 (a similar set of piston-rods, not shown, operate out of cylinders 15', 16') to be depressed against the action of springs 28, 29 which normally maintain said piston-rods in elevated or ineffective position. Each of said piston-rods carries at its lower ends a current pad 29, 30, 29', 30' said pads being connected by suitable cables 31 and 32 to a generator 33 within the car body. The cylinders 15, 16 and 15', 16' are fixedly mounted on plates 35 attached to side members 36 carried by the truss members 11, 11' and are so positioned that the piston-rods and their current pads will cooperate with the respective rail to engage the same when said pads are lowered. When the pads engage the rail, they close the circuit from the generator 33 through the rail to pass current through the rail between the pads. The presence of an internal defect within the rail will cause an increase in potential drop at that point, so that by measuring the variation in potential drop in that portion of the rail indicated by the paint mark it may be determined whether or not an internal defect exists in the rail.

For measuring the variation in potential drop from point to point along the rail in the region of the paint mark, I provide a mechanism responsive
